UNITED STATES PATENT OFFICE.

JOHN PECORA AND JOSEPH R. PECORA, OF BUFFALO, NEW YORK.

CURTAIN-ROD AND SHADE-ROLLER BRACKET.

Application filed April 15, 1922. Serial No. 553,152.

To all whom it may concern:

Be it known that we, JOHN PECORA and JOSEPH R. PECORA, citizens of the United States, residing at Buffalo, in the county of Erie and State of New York, have invented a new and useful Improvement in Curtain-Rod and Shade-Roller Brackets, of which the following is a specification.

This invention relates to curtain rod and shade roller brackets of the type adapted to be clamped to a window frame or other supporting member.

Heretofore, window brackets have been provided or proposed which either required the use of attaching screws, nails or the like which mar the woodwork to which the devices are attached. The brackets heretofore in use which have not required the use of attaching screws or the like have been of rather complicated construction and have been open to the objections that they either included one or more parts or portions which when wedged against the face of the window frame mar or spoil the finish of the portions of the frame to which they are attached, or that they have comprised a relatively large number of detachable parts which are disconnected, or readily susceptible of disconnection, one from the other when the devices are dismounted from a window frame, which has resulted in the parts becoming misplaced or lost.

The objects of the present invention are to provide a curtain rod and shade roller bracket which has no parts adapted to contact with the face of the window frame to which it is to be attached; also to provide a bracket consisting of relatively few connected parts which will not readily get out of order or become misplaced; also to provide a bracket which is readily adapted to be clamped to window frame parts or other supporting members of various different widths; also to provide a curtain rod and shade roller bracket of such construction that the weight of the shade and roller and curtain rod and hangings tends to clamp the bracket firmly to its supporting member; and to provide improvements in curtain rod and shade roller brackets in the other respects hereinafter set forth and claimed.

In the accompanying drawings:

Fig. 1 is a perspective view showing the bracket attached to a window frame.

Fig. 2 is a fragmentary sectional elevation thereof on a reduced scale.

Fig. 3 is a section on line 3-3, Fig. 2.

The bracket of this invention includes a relatively stationary clamping member 10 preferably formed with a leg portion 11 and a laterally extending part 12 which is adapted to take over the upper frame bar A of a window or the like. The portion 12 is preferably provided with a beveled flange 60 or tooth 13 for gripping the wooden frame bar or for gripping the upper edge of the rear side of the frame bar, depending upon the width of that bar.

14 designates a relatively movable clamp- 70 ing member which may be provided, as shown, with a gripping tooth or flange 15, which is preferably mounted to slide upon the leg 11 of the stationary clamp so as to be adjusted more or less toward or from 75 the stationary clamp in order to be adapted for attachment to window frame parts of different widths. The clamping member 14 is mounted to slide on the leg 11 of the stationary clamping member and also to have 80 an angular or pivotal movement with respect to the leg 11 or to the stationary clamping member 10. In the preferred means for effecting this mounting, shown, the clamping member 14 is pivoted as at 16 85 to a sleeve 17 in sliding engagement with the leg 11. It will thus be seen that the clamping member 14 and the sleeve 17 may be moved upon the leg 11 of the stationary clamp to adjust the clamps to the width of 90 the support to which they are to be attached, and then by moving the clamping member 14 angularly about its pivot the gripping jaw 15 will firmly hold the bracket in place upon the support. By reason of this pivotal 95 mounting of the movable clamping member 14 it will be seen that the weight of the shade roller, curtain rod and curtains or hangers tends to more firmly clamp the bracket to its supporting member. 100

As shown in the drawings, the movable clamping member 14 preferably extends through the leg 11 of the stationary clamping member and for this purpose the leg 11 is provided with a vertical slot 18 105 through which the clamping member 14 extends. The slot 18 is preferably formed with a plurality of enlarged recesses 19 which are adapted to receive a stop member for the purpose of holding the sleeve 17 in 110

its adjusted positions on the leg 11. In the embodiment of the invention shown, 20 designates a tie rod preferably of a diameter slightly greater than the width 6 of the slot 18 and adapted to fit within any one of the enlarged recesses 19. As best shown in Figs. 1 and 2, when this tie rod is positioned in one of the recesses 19 the sleeve is prevented from dropping any lower on the leg 11 and angular movement of the clamping member 14 in one direction about its pivot will, of course, tighten the clamps upon their supporting member.

The movable clamping member 14 is preferably provided with a forwardly extending portion 21 preferably having a hole 22 therein for the reception of the end trunnions or pintles of a usual shade roller, and forwardly of this point the extension of the movable 20 clamp is bent so as to lie in a substantially horizontal plane and is shaped to provide the semi-circular curtain rod holding portion 23. The outer end of the tie rod 20 is preferably threaded as at 24 and extends through a 25 suitable hole in the outer end of clamp 14, and 25 designates a thumb nut or the like on the threaded end of the rod and adapted to be manipulated after the bracket has been placed on a support to force the outer end of 30 the movable clamp downwardly to securely bind the bracket upon its support. It will be seen that in the embodiment shown the tie rod 20 not only provides a stop for the slidably mounted clamp member and sleeve, but also provides means for firmly clamping 35 the bracket upon its support.

26 designates a holder for the over-drape rods, which holder is preferably pivoted to the movable clamp extension as at 27.

40 The relatively stationary clamping member, the movable clamping member and the pivotal connection between the stationary and movable clamping members, are preferably so proportioned and positioned that 45 there is no appreciable contact of the parts with the face of the window frame to spoil or mar the finish of the frame. It is apparent that there are no screws or screw plates to mar the woodwork.

50 We claim as our invention:

1. In a device of the character described, a relatively stationary clamping member having a part adapted to engage a support, a sleeve slidably mounted on said stationary member, an adjustable clamping member pivoted to said sleeve and movable with said sleeve toward and from said support

engaging part and a curtain rod supporting part carried by said adjustable clamping member.

2. In a device of the character described a relatively stationary clamping member including a gripping jaw adapted to clamp on to a support, and a leg portion, a slot in said leg portion, an adjustable clamping member extending through said slot and having a gripping jaw adapted to be moved toward or from the gripping jaw of said stationary member, a sleeve mounted to slide on said leg portion of the stationary member, a pivotal connection between said sleeve and said adjustable clamping member, and a curtain rod holding part carried by said adjustable clamping member.

3. In a device of the character described, 75 the combination of a relatively stationary clamping member having a jaw adapted to engage a support, and a leg portion provided with a longitudinal slot, an adjustable clamping member slidably extending 80 through the slot in said leg portion and having a gripping jaw adapted to be moved toward or from the jaw of said stationary member, a pivotal connection between said adjustable clamping member and the leg of 85 said stationary member, and a movable stop for limiting the sliding movement of said adjustable clamping member in the slot of said leg portion.

4. In a device of the character described, 90 a relatively stationary clamping member having a gripping jaw adapted to engage a support, and a leg portion, an adjustable clamping member pivotally mounted on an axis slidably connected to the leg of said 95 stationary member, and an adjusting screw for effecting adjustments of said adjustable clamping member about its pivot.

5. In a curtain rod bracket, the combination of a relatively stationary clamping member having a jaw adapted to engage a support and a leg portion provided with a longitudinal slot, an adjustable clamping member having a jaw and a part slidable in the slot of said leg portion, a pivotal connection between said adjustable clamping member and the leg of said stationary member whereby the adjustable clamping member may be slid toward the stationary jaw or may be pivotally swung toward the 105 stationary jaw about the pivotal connection on the leg of the stationary member.

JOHN PECORA.
JOSEPH R. PECORA.
